UNITED STATES PATENT OFFICE.

WILL J. CAMERON, OF CHICAGO, ILLINOIS.

LAMP CONSTRUCTION.

Application filed July 19, 1926. Serial No. 123,358.

My present invention relates to electric lamps and has more particular reference to a miniature lamp that is especially designed for use by physicians, surgeons, dentists, and the like in making examinations, diagnosis and treatment.

Lamps of this character must, of necessity, be quite small and at the same time be capable of illuminating an area under inspection to such an extent that the operator may minutely examine the affected tissue.

Frequently, lamps of this character are mounted upon surgical and dentist instruments such as retractors, speculums, proctoscopes and the like and when thus used they must be positioned so that they will not interfere with the line of vision of the operator and at the same time give the desired illumination as well as permit the ready use of operating instruments in the cavity into which the speculums, etc., are inserted.

With my present structure I have provided a lamp that has a maximum illumination in a very small size and is designed so that the light rays will be projected from the structure in a plane of an angle to the axis of the body and said rays be magnified by passing through an integral lenticular element fused upon the side of the lamp tube. All of the lamp body excepting the lens is treated with opaque material, which permits of the use of the light rays in one direction only and prevents the rays reaching the eyes of the operator. My lamp is of L-shape, the stem (body) being slightly elongated and the arm (lens) being relatively short so that the lamp may be readily projected from or retracted into the hollow or tubular handle of the particular instrument on which it is used.

The construction of my lamp permits adjustability of the body with respect to the plug or base in assembly during manufacture so that should a slight tilt of the body be desired this can be done within a limited range of angularity.

Among the objects of my invention are the provision of a miniature lamp for surgical use that is compact and novel in construction, dependable in use, and which may be economically manufactured and placed on the market for a reasonable price. Other objects will be apparent to others after my invention is understood, and I prefer to accomplish the aforesaid objects and to carry

out my invention in substantially the manner hereinafter fully described and as more particularly pointed out in the claims. Reference is herein made to the accompanying drawings that form a part of this specification.

In the drawings:—

Figure 1 is a vertical side elevation of my lamp drawn to an exaggerated scale for clearness.

Figure 2 is a vertical axial section thereof.

Figure 3, is a side view, partly in section, illustrating the preferred manner of manufacture or assembly.

Figure 4 is a side view showing a step in the manufacture of the lamp.

Figure 5 is a schematic view in section showing the coating and cementing on enlarged scale.

The drawings illustrate schematically a preferred or typical embodiment of my invention, and in the drawings similar reference characters have been used to designate the same parts wherever they appear throughout the several views.

The base is preferably of the usual type, comprising a tubular metal shell 5, a tapered lower portion 6, terminal plate 7, and contact tip 8. The conductors or wire filaments 9 and 10 are secured at their lower inner ends respectively to the shell and tip as indicated in dotted lines in Figure 2, and said conductors or filaments are formed into a loop or coil 11 at their outer upper ends. A hollow body preferably a glass tube 12 closed at its inner lower end 13 is inserted into the base and encloses the conductors or filaments so that the latter pass through the closed end 13 for connection with the shell 95 and tip.

The hollow body is formed in the following manner:—a short glass tube 14 is heated and a lenticular element 15 is fused to one end, the opposite end remaining open, and said tube is then fused in a transverse position upon the end of the body tube 12, the axes of the tubes being at substantially a right angle to each other as indicated in Figure 3. While the tubes are heated a suitable tool is inserted through the portion of the wall of tube 14 that extends across the end of tube 12 and an opening is made that establishes communication between the tubes. The filaments may now be placed in the tube 12 with their coil 11 in proper position with respect to the lens 15 and the lower end 13

- of the tube is closed or fused together, and at the same time the end of the lateral tube 14 opposite the lens 15 is likewise closed and fused together as at 16 (Fig. 2). When the 5 body thus assembled is inserted in the base and the protruding ends of the filaments secured to their respective terminals, the space between the tube 12 and shell 5 is filled with suitable plastic cement 17 which will maintain the desired assembly when the same has 10 "set". While the cement is still plastic the lamp is placed in a test machine or calibrating device and the body may be adjusted to the proper position with respect to the base 15 by projecting the light rays upon a target in the test machine. It will be understood that during the assembly operations the interior of the body may be evacuated in any well-known manner.
- 20 After the cement has hardened or "set" the exposed surface of the body excepting the lens 15, is sprayed with zinc according to the well-known process and then suitably coated with a black paint or enamel to render the 25 same non-reflective. During this final step a band 18 is placed annularly upon the body at the place where it enters the cement or base, which band is removed after the metal spray has been applied so that an uncoated 30 space 19 remains at the place where the band was applied thus providing an insulating air gap that prevents current passing from the shell 5 to the metal coating of the body.
- A pin or stud 20 projects from the side of 35 the base shell 5 to permit the lamp being inserted in a socket terminal of the bayonet-slot type, but it will be understood the shell may be threaded for assembly with a socket of the threaded type.
- 40 What I claim is:—
1. A miniature lamp comprising a base, a body consisting of a tube extending from said base and a second tube transverse to the first tube, a filament having its ends connected to the respective terminals of the base and having a looped portion within the second tube, and a lenticular element fused to one end of the second tube whereby to project light rays laterally from said body.
  - 45 2. In a miniature lamp a tubular body in which a filament is housed and consisting of tubes arranged transverse to each other, and a lens fused to the end of one of said tubes whereby to project the light rays laterally from said body.
  - 50 3. In a miniature lamp, a tubular body, a tube closing the outer end of said body and in which a filament is looped, and a lens fused in an end of said tube whereby to project the light rays laterally from the said body.
  - 55 4. In a miniature lamp, a filament tube, a transverse tube at the end of the filament tube, a sprayed metallic coating for said filament and transverse tubes to render the same non-light-transmitting and a lens closing a light discharge orifice at one end of the transverse tube.
  - 60 5. In a miniature lamp, a tubular body, a transverse tube closing the outer end of the tubular body and housing the filament loop, a lens fused to an end of the transverse tube, and a sprayed metallic coating on said tubular body and transverse tube and rendering the same non-light-transmitting whereby said lens provides the sole means of egress for the light rays from the filaments within the body.
  - 65 6. The method of forming miniature lamps consisting in fusing a lens to the end of a tube, fusing said tube to the end of a second tube with their axes intersecting each other, forming a communication between the tubes, and tipping the other open ends of said tubes, the interior of the body being evacuated during the assembly.
  - 70 7. The method of forming miniature lamps consisting in fusing a lens to the end of a tube, fusing said tube to the end of a second tube with their axes intersecting each other, forming a communication between the tubes, tipping the other open ends to said tubes, and covering said tubes with a sprayed metallic coating, the interior of the body being evacuated during the assembly.
  - 75 8. In a lamp, a filament housing, a base in which the same is mounted, and a metallic coating on said housing to render a portion of the same non-light-transmitting, there being an uncoated annular portion on the housing adjacent the base whereby to provide an insulation air-gap between the coating and base.
  - 80 9. In a lamp, a filament housing, a base in which the same is mounted, a lens secured to a side portion of the housing to direct light rays lateral to the axis of the housing, and a metallic coating on said housing to render a portion of the same non-light-transmitting whereby the lens provides the sole means of egress for light rays from the filament, there being an uncoated annular portion on the housing adjacent the base providing an insulation air-gap between the coating and base.
  - 85 10. Signed at Chicago, in the county of Cook and State of Illinois, this 7th day of July, 1926.

WILL J. CAMERON.
